UNITED STATES PATENT OFFICE.

LOJOS BOGNÁR, OF WHITING, INDIANA.

AERIAL VESSEL.

1,108,830.

Specification of Letters Patent. Patented Aug. 25, 1914.

Application filed June 1, 1914. Serial No. 842,094.

To all whom it may concern:

Be it known that I, LOJOS BOGNÁR, a subject of the King of Hungary, residing at Whiting, in the county of Lake and State of Indiana, have invented certain new and useful Improvements in Aerial Vessels, of which the following is a specification, reference being had therein to the accompanying drawing:

10 This invention relates to aerial vessels of the dirigible type, and has for its object to provide a vessel of such class, in a manner as hereinafter set forth, for reducing the resistance to a minimum of the body of the vessel to the atmosphere during the travel 15 of the vessel.

A further object of the invention is to provide a vessel of the class referred to, with means in a manner as hereinafter set forth, for efficiently steadyng the vessel during the travel thereof.

Further, objects of the invention are to provide a vessel of the class referred to which is comparatively simple in its construction, strong, durable, conveniently steered, readily set up and comparatively inexpensive to build.

With the foregoing and other objects in view, the invention consists of the novel construction, combination and arrangement of parts as hereinafter more specifically described and illustrated in the accompanying drawings, wherein is shown an embodiment of the invention, but it is to be understood that changes, variations and modifications can be resorted to which come within the scope of the claims hereunto appended.

In the drawings, wherein like reference characters denote corresponding parts throughout the several views:—Figure 1 is a side elevation, broken away in parts, of an aerial vessel constructed in accordance with this invention, Fig. 2 is a perspective view of the hull of the vessel, Fig. 3 is a cross sectional view on line X—X Fig. 1, looking in the direction of the arrows, Fig. 4 is a section on line Y—Y Fig. 1 looking in the direction of the arrows, Fig. 5 is a top plan view of the vessel, and Fig. 6 is a front elevation.

Referring to the drawings in detail, the vessel includes a hull 7, which is substantially V-shaped in vertical section and is provided with a sharp keel 8 and a pointed 55 prow 9, which projects forwardly from the hull. In plan the top of the hull gradually

decreases in width from front to rear as at 10, and said hull 7 gradually decreases in height from front to rear whereby when the vessel is set up and traveling, the hull will extend forwardly and downwardly at an inclination. The vessel further includes a buoyant body portion, which is substantially of cigar-like form, and the said body portion comprises a lattice work frame 11, inclosed by a flexible cover 12. Each end of the body portion is closed as at 13 and 14, and each of the said ends of said body portion is pointed. The body portion can be inflated by air or gas and suitable means, not shown, is provided to permit the inflation of said body portion.

The lattice work frame supports a pair of rearwardly extending propeller shafts 15 and 16 and suitable bearings are provided in the lattice work 11 for supporting said shafts 15 and 16. The shafts 15 and 16 project outwardly from and rearwardly with respect to the said buoyant body, and each of said shafts has its rear end provided with 80 a plurality of propeller blades 17.

Fixed to each of the propeller shafts is a cog wheel 18, which is engaged by a cog chain 19 for driving the shaft and said cog chain 19, extends down and into the hull 7 and is driven from an engine shaft 20. The engine shaft 20 projects forwardly and rearwardly with respect to the engine 21 and the rear portion of the shaft 20, as above stated, is operatively connected with the 90 cog chains 19, while the forward portion of the shaft 20 is operatively connected by the driving elements 22, with a pair of forwardly projecting steering propelling shafts 23. The shafts 23 have their forward ends 95 provided with propeller blades 24, and the said forward ends of the said shafts 23 project forwardly from the prow 9 of the hull 7.

The hull 7 has depending therefrom brackets 25, carrying the axles 26, provided with wheels 27 to provide for portability of the vessel when upon the ground.

The buoyant body is connected to the top of a hull 7, by coupling means 28, which as illustrated consists of loops of wire or rope 105, and which are connected through the covering 12 with the frame 11, and furthermore extend through openings 29, in the top of the hull 7.

Mounted upon the top of the buoyant 110 body in proximity to the rear end thereof, is a frame 30, which is connected centrally

of the lower portion thereof with the buoyant body and connected to the top of said frame 30 is a flexible steadyng plane 31.

Mounted upon the top of the buoyant body in proximity to the front end thereof is a supporting frame 32 and which is mounted centrally of its lower face upon the top of the buoyant body and the said frame 32 has the top thereof provided with a flexible steadyng plane 33. The plane 33 is braced through the medium of cross members 34 which are secured to the frame 30 and to the upright member 35, carried centrally of the top of said frame 30, and the said plane 33 is reinforced through the medium of brace members 36. Secured to the frame 32 is an upright member 37, carried centrally of the top of the frame 32. The brace members 36 cross each other.

20 The frame 30 is connected to the hull by inclined braces 38 and the frame 32 is also connected to the hull by inclined braces 39.

The frames 30 and 32 are of materially greater length than the larger diameter of 25 the buoyant body and the said frames project laterally from each side of said body.

The buoyant body is so shaped as to reduce resistance to a minimum during the travel of the vessel through the air and the 30 construction of the hull also reduces resistance to a minimum during the travel of the vessel.

What I claim is:—

1. An aerial vessel comprising a hull having a pointed prow and being substantially V-shaped in cross section, said hull gradually decreasing in height from its bow to its stern and further having the top thereof gradually decreasing in width from its bow 40 to its stern, a cigar-shaped buoyant body mounted upon and secured to said hull and having the smaller portion thereof projecting rearwardly from the stern of the hull, steadyng planes mounted upon and secured 45 to the buoyant body and projecting transversely with respect thereto, driving propellers supported from said body, means for operating said propellers from said hull, steering propellers arranged forwardly of 50 the bow of the hull, and means for driving said steering propellers from said hull.

2. An aerial vessel comprising a hull substantially V-shaped in cross section and hav-

ing a pointed prow, a buoyant body gradually increasing in diameter from its rear 55 toward its forward end, of greater length than said hull, said body mounted upon and secured to said hull and projecting rearwardly from the stern of the hull, driving propellers supported from said body, steering propellers supported forwardly of said 60 hull, and means arranged in said hull and operatively connected with said driving and steering propellers for operating them.

3. An aerial vessel comprising a hull substantially V-shaped in cross section and having a pointed prow, a buoyant body gradually increasing in diameter from its rear 65 toward its forward end, of greater length than said hull, said body mounted upon and secured to said hull and projecting rearwardly from the stern of the hull, driving propellers supported from said body, steering propellers supported forwardly of said 70 hull, means arranged in said hull and operatively connected with said driving and steering propellers for operating them, and a plurality of steadyng planes mounted upon and extending transversely with respect to 75 said body.

4. An aerial vessel comprising a hull substantially V-shaped in cross section and having a pointed prow, a buoyant body gradually increasing in diameter from its rear 80 toward its forward end, of greater length than said hull, said body mounted upon and secured to said hull and projecting rearwardly from the stern of the hull, driving propellers supported from said body, steering propellers supported forwardly of said 85 hull, means arranged in said hull and operatively connected with said driving and steering propellers for operating them, and a plurality of steadyng planes mounted upon and extending transversely with respect to 90 said body, said planes arranged one in advance of the other and the forward plane being of greater length than the rear plane.

In testimony whereof I affix my signature 100 in the presence of two witnesses.

LOJOS BOGNÁR.
